(57) CLAIM

The ornamental design for a basket, as shown and described.

DESCRIPTION

FIG. 1 is a side view of a basket showing our new design;

FIG. 2 is a front view thereof;

FIG. 3 is a top view thereof; and,

FIG. 4 is a bottom view thereof.

The broken lines are for the purpose of illustrating the environment of the design only and form no part of the claimed design.

1 Claim, 2 Drawing Sheets

FIG. 1

FIG. 4
